By his Attorney,

W. H. F. G.

UNITED STATES PATENT OFFICE.

ARTHUR H. MERRILL, OF HARTFORD, CONNECTICUT.

ATTACHMENT FOR STOVES.

No. 873,254.

Specification of Letters Patent.

Patented Dec. 10, 1907.

Application filed December 10, 1906, Serial No. 347,118. Renewed October 9, 1907. Serial No. 396,665.

To all whom it may concern:

Be it known that I, ARTHUR H. MERRILL, a citizen of the United States, residing at Hartford, in the county of Hartford and

5 State of Connecticut, have invented certain new and useful Improvements in Attachments for Stoves, of which the following is a specification.

This invention relates to attachments for 10 stoves, ranges and other heaters, and has for its object the provision of an improved portable appliance which may be readily placed in position upon the stove or other heater, as will be hereinafter set forth.

15 As is well known the odors from the kitchen will frequently permeate an entire dwelling, and this is especially observable when fats are being melted, or vegetables having quantities of essential oils of odoriferous character are being cooked. It has long 20 been a desideratum to provide a fully-operative attachment which will prevent any and all diffusion of disagreeable odor, and which will always act properly in accordance with 25 the laws of nature, and which may be sold on the market, and readily placed in position on the stove or other heater.

By my invention an attachment is provided which consists of a shell of metal either 30 open at the front or closed by a door of any kind as circumstances may require, and which will be connected by a flue or flues with the draft-space in the heater leading to the chimney, the shell being so constructed 35 that no odor can be disseminated therefrom when the device is in use.

In the accompanying drawings, Figure 1 is a side elevation of an ordinary stove with my attachment applied thereto. Fig. 2 is a 40 transverse section of the top of the stove illustrating the mode of operation of the attachment, and also showing said attachment in transverse section. Fig. 3 is a plan view of the attachment, and Fig. 4 is a view 45 of an ordinary stove-lid, the central opening of which is generally covered by a small supplemental lid, and in which opening when said supplemental lid is removed the shell of the attachment may be placed.

50 Like numerals designate similar parts throughout the several views.

Referring to the drawings, the numeral 1 designates in a general way a cooking-stove which may be of any approved type, or may 55 be in the form of a gas range, or any other

kind of heater, connected to a chimney, the character of the heating appliance being immaterial so far as the present invention is concerned.

A usual pipe or conduit 2 for the products 60 of combustion leads to the chimney of the heater in the customary manner.

Designated in a general way by the numeral 3 is my improved attachment comprising in the present instance a shell 4 of metal and 65 shown provided with an open front 13 which may be closed by a door if desirable. Leading from any suitable point on the shell 4 are pipes or conduits 5 shown as of elbow construction. Two of these pipes 5 are illustrated and they 70 serve when inserted in the stove-lids to steady the shell and to hold it rigidly in place.

In the top of the stove are the usual openings covered by lids of ordinary character, the one employed in the present case for the 75 vent-pipes 5 of the attachment being represented in Fig. 4, and designated by the numeral 6, said lids having each a central opening 7 which may be closed when the attachment is not in use by the ordinary small supplemental lid (not shown). In the present construction a pair of these perforated lids is illustrated at the rear of the stove, and to place the attachment in position, all that it is necessary to do is to insert the ends of the 80 vent-pipes 5 into the openings 7 of said lids.

To illustrate the operation of the invention a skillet 8 is shown in position in one of the ordinary openings on the top of a stove or other heater, and the products driven off 90 from said skillet will pass in the direction of the arrows, through the shell 1, and through the vent-pipes 5 to the hot-air space 9 of the stove, suction being created, as indicated by arrows, in said hot-air space by the draft of 95 the chimney, and said suction operating to draw in the products passing from the vessel in which the article is being cooked to said chimney, as will be well understood.

To prevent back-draft of the products 100 emitted by the cooking or other operation, the top of the shell is preferably formed as a curved surface 10 and at the front edges above the opening in the shell, the wall is deflected and formed as a reentrant flange at 105 11, this construction forming a kind of trap or pocket which will prevent any back-draft while the attachment is in use from carrying the odors or other products being heated through the opening in the front of 110

the attachment. Usual handles 12 are attached to the shell by which it may be lifted from or placed upon the stove when desired.

Changes may be made in the form of the shell and in the construction thereof to prevent the back-draft from carrying odors into the kitchen or other room, and the vent-flues for said shell may be differently disposed than in the manner set forth without 10 departure from the invention.

Having thus described the invention, what I claim is—

1. An attachment for stoves or other heaters, comprising a shell having an open front, and a curved top wall, said curved wall merging in a depending reëntrant flange where it joins the open-front, and thus serv-

ing as a trap to prevent the emission of odors, and a vent-conduit leading from said shell and adapted to communicate with the 20 draft-space of said heater, and to secure the attachment upon the top of the heater.

2. An attachment for heaters comprising a shell having a curved top, and an open front joined to the top by a reëntrant flange 25 to prevent the emission of odors due to back-draft; and conduits leading from the shell and fitting in openings in the rear stove lids.

In testimony whereof I affix my signature in presence of two witnesses.

ARTHUR H. MERRILL.
